J. W. Hopkins,

Air Pump.

No. 99193.

Patented Jan. 25, 1870.

United States Patent Office.

JOSEPH W. HOPKINS, OF BROOKLYN, NEW YORK, ASSIGNOR TO HIMSELF AND WILLIAM H. M. PYE, OF SAME PLACE.

Letters Patent No. 99,193, dated January 25, 1870.

IMPROVEMENT IN AIR-PUMPS.

The Schedule referred to in these Letters Patent and making part of the same.

To all whom it may concern:

Be it known that I, JOSEPH W. HOPKINS, of Brooklyn, in the county of Kings, and State of New York, have invented and made a new and useful Improvement in Pumps for Air, &c.; and I do hereby declare the following to be a full, clear, and exact description of the said invention, reference being had to the annexed drawing, making part of this specification, wherein—

Figure 1 is a longitudinal section of the said pump, and

Figure 2 is a transverse section of the same, at the line xx .

Similar marks of reference denote same parts.

Heretofore, in the manufacture of air-pumps, especially large ones, for vacuum-pans in sugar-refineries, there has been great trouble experienced in keeping the pump in order, and obtaining a good vacuum, because the valves become defective, and there is no opportunity for removing obstructions with facility, and repairing any defects.

Another fruitful source of difficulty arises from the expansion or contraction of the metal, rendering the valve-seat out of true with the valve. This latter difficulty arises from the valve-seat usually being the surface of a portion of the cast-metal cylinder, or of the valve-chest.

My invention is designed to facilitate the construction of the valves, and grinding them to their seats, and to prevent the valve or seat becoming defective in operation, in consequence of expansion or contraction.

To effect these objects, I employ separate detachable valve-seats, fitted so that they can be mounted with the valves, and prepared for use while separate from the cylinder, and then, when completed, the valve-seat can be slipped into place, and the parts applied thereto. This enables me to make the valves and seats with the greatest care and accuracy, and defects in the metal forming the valve-seats, or in the workmanship, are avoided.

In the drawing—

a is the cylinder, forming, with the piston b , and heads $c c$, a pump for air, water, or other fluids, and these parts are to be of any usual or desired size or proportions.

d is the induction-pipe, leading into the spaces $e e$, below the valves $f f$, that are above the seat-plates i , and within the spaces h , leading to the induction-ports l .

$m m$ are the eduction-ports, that diverge, as seen in fig. 2, to come up beneath the respective valves f' ; and n are the valve-covers, and o , the eduction-pipes and passages.

The valves $f f'$ are all formed as disks upon spindles 2, and small spiral springs are employed to press the valves down to their seats.

These valves are formed in ranges or groups, and the seat-plate i of each group carries, by pillars 4, the stem-bar r , through which the valve-stems pass.

The seat-plates i are formed with dovetailed edges, and the recesses receiving them are similarly shaped, so that after each group of valves has been properly constructed, and the valves ground and fitted each to its seat, the seat-plate can be slipped into its place, and then the cap put upon the pump.

This construction allows for removing any group of valves with great facility, for freeing any valve from an obstruction, or regrinding the valve to its seat.

By winding the spring for each valve in a conical form, considerable play can be given to the valve, without the possibility of the spring being injured.

If desired, each valve may have a face of India rubber, to prevent the necessity of grinding the valve to the seat.

This pump, when employed for maintaining a vacuum in sugar or other apparatus, may have a small quantity of water in it, to fill the otherwise unoccupied spaces and passages at the end of each stroke.

What I claim, and desire to secure by Letters Patent, is—

The movable seat-plates i and stem-bar r , in combination with the disk-valves and the cylinder and piston of a pump, substantially as and for the purposes set forth.

In witness whereof, I have hereunto set my signature, this 29th day of June, 1869.

JOSEPH W. HOPKINS.
